DESIGN FOR A DROP LEAF TABLE OR SIMILAR ARTICLE

Herman E. De Vries, New York, N. Y., assignor to H. T. Cushman Mfg. Co., North Bennington, Vt.

Application May 17, 1933. Serial No. 48,147

Term of patent 3½ years

To all whom it may concern:

Be it known that I, HERMAN E. DE VRIES, a citizen of the United States, residing at New York city, in the county and State of New York, have invented a new, original, and ornamental Design for a Drop Leaf Table or Similar Article, of which the following is a specification, reference being had to the accompanying drawing, forming a part thereof.

Figure 2 is a similar view on a reduced scale and showing the table leaf held in upward position by the leaf support element.

I claim:

The ornamental design for a drop leaf table or similar article, as shown and described.

HERMAN E. DE VRIES.
